INVENTORS

UNITED STATES PATENT OFFICE

95,217

DESIGN FOR A BLOUSE OR SIMILAR ARTICLE

Irving H. Bernstein and Murray Presslaff,
New York, N. Y.

Application February 21, 1935, Serial No. 55,526

Term of patent 3½ years

To all whom it may concern:

Be it known that we, Irving H. Bernstein and Murray Presslaff, citizens of the United States of America, residing in Manhattan, county of New York, and State of New York, have invented a new, original, and ornamental Design for a Blouse or Similar Article, of which the following is a specification, reference being had to the accompanying drawing, forming part thereof, wherein,

We claim:

The ornamental design for a blouse or similar article, substantially as shown.

MURRAY PRESSLAFF.
IRVING H. BERNSTEIN.
